UNITED STATES PATENT OFFICE.

CHESTER G. VAN BUREN, OF CHICAGO, ILLINOIS.

LOOSE-LEAF BINDER.

Application filed November 4, 1926. Serial No. 146,111.

My invention relates to improvements in loose leaf binders and has for its object the provision of an improved construction of this character which is strong and efficient in use and capable of economical manufacture.

Other objects will appear hereinafter.

The invention consists in the combinations and arrangements of parts hereinafter described and claimed.

The invention will be best understood by reference to the accompanying drawings forming a part of this specification, and in which,

15 Fig. 1 is a perspective view of a loose leaf binder embodying the invention;

Fig. 2 is a section taken substantially on the line 2—2 of Fig. 1;

Fig. 3 is a transverse section of one of the 20 cover members employed in the binding shown as detached;

Fig. 4 is a similar view of the other cover member;

Fig. 5 is a section taken substantially on 25 the line 5—5 of Fig. 4;

Fig. 6 is a plan view of a modified form of construction;

Fig. 7 is an enlarged section taken on the 30 line 7—7 of Fig. 6;

Fig. 8 is an enlarged section taken on the line 8—8 of Fig. 6;

Fig. 9 is a view of one of the cover members detached;

Fig. 10 is a view of the other cover member 35 detached; and,

Fig. 11 is a section taken substantially on the line 11—11 of Fig. 10.

The form of construction illustrated in Figs. 1 to 5 inclusive comprises two cover members 12 and 13 detachably secured or bound together in book form. To effect such binding, each cover member is provided adjacent its bound edge with projecting strips 14 and 15 projecting toward the other cover member and cooperating with each other. Each of said strips constitutes one leg of a corresponding angle iron, the other leg of which is suitably embedded and secured in the corresponding cover member as shown.

50 The angle iron leg 14 is provided at its ends with notches 16 and the corresponding cover member 12 is provided with two bowed leaf binding springs 17 as shown. The other strip or cover member 15 is provided at its ends with back-turned guard members 18 and 19 arranged as shown to provide a space for the

reception of the corresponding ends of the strip 14. A pin 20 traverses the space enclosed by the guard 18 and a latch spring 21 is provided to cooperate with the opposite 60 guard 19. The latch spring 21 is secured in place by means of a rivet 22 and is provided with a lip or tang 23 projecting through a corresponding opening in the strip 15 and arranged automatically to engage the corresponding notches 16 when strip 14 is inserted. The latch spring 21 is also provided with an inwardly turned lip 24 engaging around the end 19, said lip 24 striking the end 19 when said latch spring is pressed back sufficiently to release the latch lip 23 from notch 16 thus preventing further movement of said latch spring and consequent injury thereto.

By this arrangement it will be noted that a plurality of loose leaves 25 may be readily 75 assembled or arranged on the cover member 13 with their edges resting against the corresponding strip 15. To bind the leaves 25 in place all that is necessary is to insert and engage the notch 16 at the corresponding end 80 of the strip 14 with the pin 20 and then swing the other end of the strip 14 downwardly until the notch 16 in the other end automatically engages the latch lip 23, thus locking the strips in cooperating relation with each other. 85 This action causes springs 17 to rest upon and bind the loose leaves 25 in place. When it is desired to release leaves 25, all that is necessary is to press outwardly upon the lip 24 to release the latch 23 from the corresponding notch 16 whereupon the spring 17 will 90 separate the cover members, thus permitting of ready removal of said leaves.

The modification illustrated in Figs. 6 to 11 inclusive provides for sufficient adjustment to accommodate a wide range in the number of leaves 25 which may be bound. To this end, one of the strips 14' is provided with a plurality of notches 16' in its ends and the corresponding cover members are provided with a double bowed leaf spring 17' as shown. The other strip 15' is made also of a height corresponding with the strip 14' and is provided with corresponding back turned guide guards 18' and 19' to receive the ends of the strip 14'. In this case two of the latch springs 21 are provided, one at each end. Otherwise the construction is the same as that already described. By this arrangement it will be noted that piles of loose leaves 110 25 of various depths may be placed upon cover member 13 and readily bound in place

by inserting the strip 14' in the space behind the guide guards 18' and 19' and pressing downwardly thereon. This will cause the latch spring 23 to engage automatically with 5 the notches 16' and lock the cover 12 in binding position to hold said leaves securely, the different notches 16' permitting of a wide range of adjustment to accommodate different numbers of leaves 25, as will be readily 10 understood. When it is desired to release the leaves, all that is necessary is to press outwardly on one or the other of the lips 24 whereupon the spring 17' will force the cover member 12 upwardly when the latch 23 is 15 raised from the corresponding notch 16'.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 25 appended claims.

Having described my invention what I claim as new, and desire to secure by Letters

Patent is:

1. A binder comprising two cover members 30 bound together in book form, each cover member being provided at its bound edge with a strip projecting therefrom toward the other cover member, the ends of one of said strips being bent back to form guide guards; a 35 spring latch member on one end of said last mentioned strip cooperating with the corresponding guard, there being means on the other strip to detachably engage said latch; a detachable engagement between the other 40 ends of said strips; and a leaf spring on one cover member and arranged to rest upon and bind leaves between said cover members, substantially as described.

2. A binder comprising two book cover

members, each cover member being provided 45 at one of its edges with an angle iron having one leg secured in the body of the cover, the other leg projecting therefrom to form a securing strip; one of said strips provided with back-turned ends forming guide guards, 50 means associated with said guide guards and cooperating means associated with the ends of said other strip for detachably securing said strips together to form a book with said cover members; and a leaf spring on one 55 cover member and arranged to rest upon and bind leaves between said cover members, substantially as described.

3. A binder comprising two book cover members, each cover member being provided 60 at its bound edge with a strip projecting therefrom at an angle; one of said strips provided with back-turned ends forming guide guards; means associated with said guide guards and cooperating means associated 65 with the ends of said other strip for detachably and adjustably securing said strips together; and a leaf spring on one cover member and arranged to rest upon and bind leaves between said cover members, substantially as 70 described.

4. A binder comprising two cover members bound together in book form, each cover member being provided at its bound edge with a strip projecting therefrom toward the 75 other cover member; one of said strips being provided with back-turned ends forming guide guards and the other strip being provided in its ends with corresponding notches; spring latches cooperating with said guards 80 and provided with means engaging said notches; and a leaf spring on one cover member and arranged to rest upon and bind leaves between said cover members, substantially as described.

In testimony whereof I have signed my name to this specification.

CHESTER G. VAN BUREN.
